(57) **CLAIM**

The ornamental design for a hand tool shaft, as shown and described.

DESCRIPTION

FIG. 1 is a perspective view of the hand tool shaft showing our new design, with 3D construction lines indicating a recess, extending along the entire length of the hand tool shaft, at 6 locations along the length of the tool shaft;

FIG. 2 is a top view of the hand tool shaft;

FIG. 3 is a bottom view of the hand tool shaft;

FIG. 4 a first side of the hand tool shaft;

FIG. 5 is a second side view of the hand tool shaft;

FIG. 6 is a first end view of the hand tool shaft; and,

FIG. 7 is a second end view of the hand tool shaft.

The broken line showing of the hand tool shaft forms no part of the claimed design.
